UNITED STATES PATENT OFFICE.

MARTIN A. ROHMER, OF FLORENCE, NEBRASKA.

ROTARY ENGINE.

1,250,663.

Specification of Letters Patent. Patented Dec. 18, 1917.

Application filed February 17, 1917. Serial No. 149,239.

To all whom it may concern:

Be it known that I, MARTIN A. ROHMER, a citizen of the United States, residing at Florence, in the county of Douglas and State of Nebraska, have invented certain new and useful Improvements in Rotary Engines; and I do hereby declare the following to be a full, clear, and exact description of the invention, such as will enable others skilled in the art to which it appertains to make and use the same.

The invention relates to improvements in rotary engines.

The object of the present invention is to improve the construction of rotary engines designed for the use of steam or other fluid pressure and equipped with means for introducing the fluid pressure into the engine centrally of the rotary piston and of discharging the said pressure at the periphery of the rotary piston without the friction which would ordinarily result from such a discharge.

With these and other objects in view, the invention consists in the construction and novel combination of parts hereinafter fully described, illustrated in the accompanying drawings and pointed out in the claims hereto appended; it being understood that various changes in the form, proportion, size and minor details of construction, within the scope of the claims, may be resorted to without departing from the spirit or sacrificing any of the advantages of the invention.

In the drawings:

Figure 1 is a longitudinal sectional view partly in elevation of a rotary steam engine constructed in accordance with this invention.

Fig. 2 is a transverse sectional view of the same.

Fig. 3 is a detail perspective view of one of the arcuate outlets.

Like numerals of reference designate corresponding parts in the several figures of the drawings.

In the accompanying drawings, in which is illustrated the preferred embodiment of the invention, the rotary engine comprises in its construction a rotary piston 1 mounted within a sectional casing 2 and provided at opposite sides with solid and hollow shaft sections or shafts 3 and 4, which are journaled in suitable bearings of standards 5. The rotary piston is provided with a cen-

tral inlet chamber 6 and it has a spiral or convolute passage or channel 7 extending from the central inlet chamber 6 to the periphery of the rotary piston, the outer end 8 being slightly enlarged, as is shown, to facilitate the discharge of steam or other fluid pressure from the rotary piston. The shafts may be provided at their inner ends with suitable heads 9 secured in recesses 10 of the rotary piston by screws or other suitable fastening devices, but the mounting of the rotary piston may be varied, as will be readily understood. The casing, which is composed of two circular sections provided with peripheral flanges 11, has suitable packing 12, which may be in the form of one or more packing rings, and the said sections of the outer casing are provided with central tubular extensions 13 having annular attaching flanges 14, which are secured by bolts or other suitable fastening devices to corresponding flanges 15 of the standards 5. The tubular shaft extends beyond the bearing of the adjacent standard 80 and is arranged within a coupling section 16 to which a steam feed pipe 17 is connected, and one or more packing rings 18 may be employed for providing a steam-tight joint or connection between the hollow rotary 85 shaft and the tubular member or coupling section 16. The tubular member or coupling section 16 is provided at the standard with an annular flange 19, which is bolted or otherwise secured to a flange 20 of the 90 standard.

The casing, which is of greater diameter than the rotary piston, is provided at opposite sides with packing rings 21, which may be of any desired number and which are interposed between the rotary piston and the casing to form steam-tight joints or connections at the outer portion of the said piston. Within the space beyond the rotary piston are mounted a plurality of separate 100 arcuate outlets 22 consisting substantially of rectangular frames composed of straight radially arranged sides and curved ends 23, which are provided with openings 24 for the reception of screws 25 or other suitable 105 fastening devices for securing the outlets in proper position at the peripheral portion of the casing in spaced relation with the rim of the same to form an outer circumferential space 26 to permit the steam or other fluid 110 pressure to pass to exhaust ports 27, which may be of any desired number to secure the

necessary rapidity of exhaust. The number of the outlets may be varied and they may be arranged at the desired point around the periphery of the outer casing and they can, 5 by the fastening means employed, be set as close together or as far apart as desired, suitable perforations being provided for the screws 25. The steam or other fluid pressure entering the engine at the inlet chamber 6 10 contacts with the curved wall of the spiral passage and exerts a pressure against the same and produces a rotary motion of the piston and in passing out through the outer terminal portion of the spiral or convolute 15 passage it contacts with the radially arranged sides of the outlets and is directed by the same into the annular circumferential space between the outlets and the rim of the casing so that the steam will not be 20 deflected back against the rotary piston and interfere with the free rotary movement of the same. The friction incident to such back action or contact of the steam with the rotary piston is thereby eliminated. The sectional formation of the outer casing affords 25 ready access to the interior of the engine and will enable the parts to be readily assembled and separated for renewing the packing or any other purpose.

30 What is claimed is:

1. A rotary engine of the class described including a casing, a rotary piston having a central inlet chamber and provided with a spiral passage extending from the inlet 35 chamber to the periphery of the rotary piston, said rotary piston being arranged within the casing and the latter being extended beyond the periphery of the rotary piston and having an exhaust port, and a plurality 40 of arcuate outlets consisting of radially arranged side and curved connecting ends and extending across the casing beyond the rotary piston and arranged in spaced relation with the rim of the casing to provide an 45 outer annular space, the radially arranged sides of the outlets being adapted to deflect the steam or other fluid pressure into the circumferential space and relieve the rotary piston of friction.
2. A rotary engine of the class described 50 including a casing, a rotary piston having a central inlet chamber and provided with a spiral passage extending from the inlet chamber to the periphery of the rotary pis-

ton, said rotary piston being arranged with- 55 in the casing and the latter being extended beyond the periphery of the rotary piston and having an exhaust port, a plurality of arcuate outlets consisting of radially arranged side and curved connecting ends and 60 extending across the casing beyond the rotary piston and arranged in spaced relation with the rim of the casing to provide an outer annular space, the radially arranged sides of the outlets being adapted to deflect 65 the steam or other fluid pressure into the circumferential space and relieve the rotary piston of friction, and fastening devices piercing the casing at opposite sides thereof and extending into openings in the 70 arcuate connecting ends of the outlets and detachably secured to the same within the casing.

3. A rotary engine of the class described including spaced standards provided with bearings and having annular flanges thereat, a stationary casing composed of circular sections secured together at their peripheries and provided with central tubular extensions having annular flanges secured to the 75 flanges of the standards, a rotary piston arranged within the casing and having a central inlet chamber and a spiral or convolute 80 passage or channel extending from the central chamber to the periphery of the piston, 85 said piston being also provided at opposite sides with recesses, solid and hollow shafts having heads secured in the said recesses, said shafts being mounted in the bearings and a hollow shaft being extended beyond 90 the bearing at the outer side thereof and communicating at its inner end with the central chamber, fastening means for securing the flanges of the casing to the flanges 95 of the standards, a coupling member secured to one of the standards and receiving the projecting end of the hollow shaft and provided with packing, and separate outlets mounted within the casing at the outer portion thereof and presenting deflecting faces 100 to the channel of a rotary piston.

In testimony whereof I affix my signature in presence of two witnesses.

MARTIN A. ROHMER.
